UNITED STATES PATENT OFFICE.

AUSTIN F. JACKSON, OF TAUNTON, MASSACHUSETTS.

DESIGN FOR A TEAPOT OR LIKE ARTICLE.

SPECIFICATION forming part of Design No. 28,688, dated May 24, 1898.

Application filed December 27, 1897. Serial No. 663,775. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for Teapots and Like Articles, of which the following is a specification, reference being had to the accompanying drawings, forming part thereof.

10 My invention is in the nature of a new design for tea, coffee, chocolate, and hot-water pots and like articles.

15 Figure 1 is a side elevation of a teapot embodying my design with outline cross-sectional views of the various parts juxtaposed. Fig. 2 is an outline plan of the body portion.

20 The essential features of the body portion are a generally oblong shape in horizontal section, as shown in Fig. 2, and a large lower portion A of convex outline, and a smaller upper portion B of concave outline. The lower and larger convex portion has ornamental upright convex corrugations a on its flattened sides, rounded ends c c, and four sets of vertically-extending concave flutings b b b b disposed between the convex corrugations a and the rounded ends c c and extending in similar concave flutings b' b' b' b' upwardly along the smaller upper portion B of the body. A 25 base D of a shape corresponding generally to the body portion spreads out beneath the lower portion A of the body and has on each side a symmetrical ornament d of a double-scroll pattern, while another symmetrical ornament e of a double-scroll pattern is arranged at the margin of the upper portion B on each side.

30 The essential features of the spout S are a reversely-curved outline with the cross-section shown and having at its lower end or root portion a series of scallops f, joining onto the body portion A, with parallel tapering corrugations f' running up along the sides of the spout. Scrolls f² are at the top of this root portion, and foliated scrolls f³ and f⁴ are ar-

ranged, respectively, at the top and bottom of the spout.

35 The essential features of the top T are a generally conical shape with reversely-curved sides concave at the bottom and convex at the top, with a series of upwardly-converging corrugations t and t', those shown at t on the sides extending from the apex a little below the middle line of the top, while those t' at the ends extend all the way down to the lower edge of the top. An ornamental ring-shaped finial f² surmounts the apex.

40 The essential features of the handle are the shape and cross-section shown with a scalloped and spreading root portion h where it joins onto the upper portion of the body and with a scalloped scroll h' on each side. A foliation h², with scrolls at top and bottom, connects the bottom of the handle to the lower portion of the body. The middle part of the handle is bent at its upper end at a generally acute angle, has longitudinal corrugations h³ on the sides, and is surmounted with a foliation h⁴ and scroll h⁵ at the top.

45 Having thus described my invention, what I claim as new is—

1. In a design for a teapot, or like article, the body having the shape and ornamentation as herein shown and described.

2. In a design for a teapot, or like article, the handle having the shape and ornamentation as herein shown and described.

3. In a design for a teapot, or like article, the spout having the shape and ornamentation as herein shown and described.

4. In a design for a teapot, or like article, the top having the shape and ornamentation as herein shown and described.

5. The design for a teapot or like article having the shape and ornamentation as shown and described.

AUSTIN F. JACKSON.
